REFRIGERATOR AND TEMPERATURE
CONTROL DEVICEVirginius W. Moody, Jackson Heights, N. Y., as-
signor to Reynolds Metals Company, New York,
N. Y., a corporation of Delaware

Application March 9, 1935, Serial No. 10,160

2 Claims. (Cl. 62—91.5)

The present invention has to do with refrigeration and relates particularly to a valve used in a brine circulating system.

It has been common to employ mechanical valves in brine circulating systems. Such valves require packing and ordinarily use non-metallic facings in the valves. From time to time, adjustments are required and such valves are seldom leak-proof. The facings generally are of leather which is quickly devitalized because of the chemical characteristics of the brine. The leather warps or decomposes with a resulting inaccuracy in the seating of the valve. The systems that employ mechanical valves have difficulties arising from the presence of dirt and debris in the brine. Such dirt and debris has a tendency to collect in the valve to prevent the valve from properly seating.

Over these disadvantages, the present invention provides a system in which but one valve adjustment is ever necessary and that is the initial adjustment or assembly. There are no moving parts in the valve; there is no decomposition of the valve material; and the presence of dirt and debris does not effect its operation. There is no possibility of jamming the valve, there is no problem of leakage from warping, shrinking or improper adjustments, and the valve itself provides a safety measure not possible in any valve having moving mechanical parts.

The objects of the invention, among others, include the following:

A liquid valve suitable for use in the brine circulating system of refrigerating apparatus;

A valve free from mechanical parts and free from materials subject to decomposition in the brine of such a system;

A valve free from packings of any sort and suitable for use in a brine circulating system;

A valve in which mercury is substituted for mechanically moving parts and which is suitable for use in a brine circulating system; and

A novel construction for a mercury trap valve. These objects, and such other objects as may hereinafter appear, are obtained by the novel construction, unique arrangement, and improved combination of the several elements combined in the form of the invention schematically illustrated in the accompanying single sheet of drawing.

The apparatus shown in the drawing is but one form which the invention may assume. The construction and arrangement of parts is a matter of great flexibility. It is possible to modify

the various elements shown to provide a satisfactory circulatory system for the smallest of household refrigerators as well as for the largest of cold storage plants.

Like reference characters are used to designate similar parts in the drawing and in the description hereinafter given.

The schematic representation of a circulatory system embodying the subject matter of the present invention employs solidified carbon dioxide as a refrigerant. The gas which is released by the sublimation of such carbon dioxide energizes the circulating system. In the illustrated form of the invention, there is a container 10 having a cover 11. There is between the container 10 and the cover 11 a suitable gasket 12 to make the container gas-tight when the device is functioning. Adjacent the top of the container 10 is an aperture to which a gas conduit 13 is connected. At the bottom of the container 10 are two apertures. In the container and of suitable form and arrangement, is a coil 14, one end 15 of which projects through one of the apertures adjacent the bottom of the container. The other end 16 of the coil 14 projects through the second aperture adjacent the bottom of the container.

The connection of the gas conduit 13 and the insertion of the coil 14 in respect to the several apertures in the container is such that there can be no leakage of gas between the conduit 13 and container 10 and around the apertures through which the ends 15 and 16 of the coil project.

The system for circulating brine comprises a conduit 17 connected to the end 16 of coil 14 and a conduit 18 connected to the end 15 of said coil 14. In the conduit 18 are a number of coils 19 which are disposed in the space, room or chamber to be refrigerated. From coils 19, a suitable conduit 20 extends for the return of the brine to the circulating system.

To urge the refrigerating brine into the conduit 17 running to the coil 14 and to receive the brine discharged from the circulatory system, discharged from conduit 20, two tanks 21 and 22 are provided. These are generally superposed. They may be in the form of a single tank having a partition suitably disposed thereacross. The capacity of the lower tank 22 should be less than the capacity of the upper tank 21 so that the entire contents of the circulatory system may be forced out of the lower tank into the upper tank with ample room therefor to prevent an overflow.

In tank 21, there is a vent to charge the system with brine. The vent is closed by cap 23. In 55

addition, there is a breather tube 24 which extends preferably from the top wall of the tank 21 to the open atmosphere. The brine discharge conduit 20 empties in the tank 21 preferably at or adjacent to the top thereof.

In tank 22, there is an aperture adjacent to the bottom thereof to receive the end of the conduit 17 through which brine flows to the cooling coil 14 within the container 10. Beneath the tank 22 is a mercury trap. This comprises a vessel 25 of relatively small capacity directly connected to the tank 22 by a conduit 26. The mercury trap 25 has a substantially flat bottom wall 27 which has therein a small depression or pocket 28. The pocket 28 is preferably shallow.

Extending upwardly through the mercury trap 25 is a tube 29, the lower end of which is in a horizontal plane in substantial alignment with the flat wall 27 forming the bottom of the mercury trap 25. The end of the tube 29 preferably is about a quarter of an inch from the bottom of pocket 28 in a household refrigerator, the lowermost section of the tube 29 being about $\frac{1}{4}$ inch removed from any adjacent mercury supporting surface. The tube 29 extends out of the top wall 30 of the mercury trap 25 through the bottom wall of the container 22 to contiguity with the bottom wall of the container 21. As shown, tube 29 terminates in a funnel-like or flaring section 31 which has a vertical flange 32 thereabout.

In the mercury trap 25, there is at the bottom of the pocket 28 a discharge orifice which is suitably sealed by a screw block 33 or the like and there is a vent at a higher level in the trap 25 sealed in the same manner by screw block 34.

An air escape tube 36 may be disposed within the tube 29 connecting the tank 21 and the mercury trap 25. The lower end of the tube 36 is at a slightly higher level than the normal level of the mercury in the trap 25, the upper end of the tube 36 to extend into proximity with the top of the tank 21. The upper end of the tube 36 should be above any possible level that the brine may reach in the upper tank 21. The air tube 36 permits of the escape of air which might otherwise be trapped in the tube 29 and which because of the mercury at one side and the brine at the other side might tend to produce a seal in the tube 29 preventing the brine from flowing freely downwardly in the tube 29.

There is a gas conduit 13, as previously indicated, extending from the container 10. Conduit 13 has one leg 38, extending to the upper section of the tank 22. It has another leg 39 which extends to a temperature controlled gas valve 40. The temperature control valve 40 when open allows gas to escape into a conduit 41 which may be connected to the breather tube 24 running from the tank 21 and heretofore described or it may discharge directly to the atmosphere if preferred.

When the apparatus is assembled in the manner shown in the schematic drawing, it is rendered operable by closing the mercury drain vent 33. Mercury is then poured into the mercury trap 25 through the upper vent in the trap 25. Thereafter the screw plug 34 for such upper vent is forced home to seal the mercury trap 25.

The depth of the mercury pool should be slight even in large installations. A relatively thin submergence is desirable, say, one-sixteenth of an inch. The greatest depth of the mercury will be in the pocket 28 in the mercury trap 25 below the end of the tube 29. But one-sixteenth inch of the mercury in such pool should extend up the walls of said tube 29 from the bottom edge. This

will result in a relatively shallow pool of mercury over the upper side of wall 27.

Suitable brine is then poured into the tank 21 through the vent therein. The quantity of brine is measured so that the amount is substantially the capacity of the lower tank 22. This will be less than the capacity of the tank 21. Such brine will flow into the tube 29 and downwardly into the mercury trap 25. The height of the column of brine will be such that it will displace the mercury in and collected about the lower end of the mercury tube. The major portion of the brine will flow through the mercury trap 25, and flow upwardly into the tank 22, there remaining of course a relatively small quantity of such brine in the tube 29 above the mercury collected in the pocket 28. The air pipe 36 is useful at this time and during the operation of the device to prevent trapping of air within the tube 29 and such tube prevents the possibility of the mercury, in conjunction with trapped air, forming a seal in such tube which would prevent the ready flow of the brine through the tube 29 in the manner just described. After the cap 23 is placed on the vent in tank 21, solidified carbon dioxide is then placed in the container 10 and the cover 11 fastened securely thereon to prevent the escape of gas.

The solidified carbon dioxide immediately begins to sublimate. In so doing, it builds up a gas pressure within the container 10. Such pressure extends outwardly through the gas conduit 13 and into the upper section of the brine tank 22. The escape of the gas through the valve 40 is prevented for such valve is thermostatically controlled and will open only when the atmosphere thereabout has reached a predetermined low level. The thermostat is marked 37.

As the amount of gas which sublimes from the solid carbon dioxide increases, its pressure increases and it establishes a pressure within the brine tank 22 equal to that within the container 10. Such pressure is distributed throughout the contents of the tank 22 and brine is forced therefrom into the cooling coil 14 within the container 10 to make room for the increasing volume of gas.

Such pressure also effects the mercury in the mercury trap 25 and the mercury which is immiscible with the brine is forced upwardly in the tube 29. As mercury is displaced upwardly in such tube from the pocket 28, the excess volume of mercury within the mercury trap 25 runs into the pocket so that until a certain definite limit of pressure is attained, only mercury will be forced upwardly in the tube 29. As the mercury is approximately thirteen times heavier than the brine, that is, has a specific gravity thirteen times greater than that of the brine, brine will be forced upwardly thirteen inches in conduit 17, coil 14, conduit 18, and coil 19 for every inch of mercury that is forced upwardly in the tube 29. If four inches of mercury are forced upwardly in the tube 29, the brine in conduit 17, coil 14, conduit 18 and coil 19 will be forced approximately fifty-two inches, which is as great a height as is necessary in ordinary household refrigeration.

With the continued sublimation of the solidified carbon dioxide, the major portion of the brine is forced out of the tank 22 through the conduit 17 to the cooling coil 14 where it is rapidly chilled by the solidified carbon dioxide resting upon such coil 14, into the conduit 18, and through the refrigerating coils 19, and from

the refrigerating coils 19 where there is heat exchange with the contents of the chamber within which said coils are disposed, through the discharge conduit 20 and into the upper tank 21. As the brine is discharged into the tank 21, the air therein is displaced therefrom and escapes by way of the breather 24. The breather 24, therefore, prevents any possibility of gas pressure into the tank 21.

10 The thermostat 37 is disposed in such positive juxtaposition to coils 19 that before all of the brine from tank 22 shall have passed into tank 21, such brine will sufficiently chill the thermostat 37 to open valve 40. Should a single surge 15 of brine through coil 19 not lower the temperature of the cabinet or chamber to the desired level, the then chilled thermostat 37 will quickly absorb heat from the chamber and expand to close valve 40. Another surge of brine will then 20 be sent into coils 19. This operation will be repeated indefinitely until the temperature of the cabinet or chamber has been reduced sufficiently to maintain valve 40 in a fixed open position and so permit the continuously sublimating gas 25 to escape through vent 24. At any time during the movement of the brine, the atmosphere within the chamber to be cooled has reached a predetermined low level, the thermostatically controlled valve 40 will open and the gas in the 30 container 10 and in the tank 22 and in the conduits therebetween will escape through the valve 40 and breather 24. The entire system will immediately be reduced to atmospheric pressure.

As soon as the valve 40 opens and the gas 35 pressure within the whole system is reduced to atmospheric, whatever brine has collected in tank 21 flows back through tube 29 into mercury trap 25 and then outwardly through tube 26 into tank 22. That part of the brine collected in the 40 conduits and elsewhere in the system other than in tank 21 will flow back to tank 21.

Should the thermostatically controlled valve 40 for any reason fail to work, no harm may result. As the gas pressures are built up in the tank 22, the brine is forced therefrom and eventually all of such brine above the level of the conduit 17 will be driven from lower tank 22. When this occurs, the gas may escape through the circulatory system into the tank 21 and to 45 the atmosphere by way of the breather 24.

Should the circulatory system for any reason become clogged, the increased pressure in the tank 22 will be communicated to the mercury trap 25 and eventually all of the mercury in the trap 25 forced upwardly in the tube 29 except 5 a small quantity thereof which would remain in the pocket 28. When the amount of mercury forced upwardly in the tube 29 reduces the supply of mercury in the trap 25 to a predetermined amount, then brine will be forced into the tube 10 29 and eventually all of the brine will be driven from the trap 25 along with the mercury into the tube 29. When this abnormal condition is attained, then gas will follow the mercury and 15 brine up the tube 29 bubbling therethrough and escaping into the tank 21 and from the tank 21 to the atmosphere by the breather 24.

What is claimed as new and is desired to be secured by Letters Patent of the United States is:

1. A circulatory system for a cooling medium 20 and comprising a storage tank, a discharge tank to receive the medium from said storage tank, a conduit between said tanks and having refrigerating coils therein, a return conduit from the discharge tank to the storage tank, means in said 25 storage tank to receive a quantity of mercury for forming a well about the discharge end of said return conduit, and means in said discharge tank for trapping mercury forced out of said storage tank into said discharge tank through said return conduit.

2. A system for the circulation of a cooling medium and comprising a storage tank, a discharge tank above said storage tank, a conduit between said tanks and having refrigerating coils 35 therein, a return conduit from the discharge tank to the storage tank, means in said storage tank for receiving a body of mercury, an end of the return conduit being immersed in said body of mercury, a conduit extending from within the return conduit to the atmosphere for the escape of gas trapped in said return conduit, means for increasing the pressure in said storage tank to force cooling medium therefrom through 40 the refrigerating coil conduit and into the discharge tank, and thermostatically actuated means for reducing such pressure.
